UNITED STATES PATENT OFFICE.

KNUTE W. OLSON, OF ST. PAUL, MINNESOTA.

SAFETY DEVICE FOR AVIATORS.

1,229,503.

Specification of Letters Patent. Patented June 12, 1917.

Application filed August 28, 1916. Serial No. 117,387.

To all whom it may concern:

Be it known that I, KNUTE W. OLSON, a citizen of the United States, residing at St. Paul, in the county of Ramsey and State 5 of Minnesota, have invented a new and useful Improvement in Safety Devices for Aviators, of which the following is a specification.

My invention relates to a safety device 10 for aviators which will securely and comfortably hold the aviator in his seat and also allow him to quickly and positively release himself if he so desires, such as in case of an accident or a fall of his machine. There 15 have been various harnesses made for this purpose but they have not been practical or simple so that the operator of the aeroplane could drive in comfort and with the assurance of being securely held to his machine 20 and at the same time assured that should he desire he could instantly release himself from the aeroplane.

It is an undoubted fact that many aero 25 fatalities could have been avoided if the aviator could have released himself from his machine in time.

It is an important feature of my invention to securely hold the aviator about the body and legs as this will prevent him from 30 being thrown into a doubled up position which would make it impossible for him to operate his levers or release himself.

It is also an important object of my invention that the aviator can quickly and 35 easily fasten himself to his machine. My device is simple in operation and easily operated. In the drawings which form part of this specification—

Figure 1 is a perspective of the portion 40 of an aeroplane frame showing an aviator in position in his seat and with my improved safety device.

Fig. 2. is a perspective of the portion of 45 the aeroplane frame with my device attached thereto.

Figs. 3 and 4 are details illustrating the construction of the mechanism.

In the drawing A, illustrates an aeroplane 50 frame of ordinary construction, B illustrates the harness secured to an aviator, and C illustrates the mechanism which is adapted to detachably secure the harness to the aeroplane frame work.

The harness is of simple construction having 55 a belt 2 which is adapted to be fastened about the waist of the aviator. Bands 3,

pass around each leg respectively of the aviator and the bands 3 have an extension piece or strap 4 to the end of which is secured a ring or snap 5 or any suitable means 60 which is adapted to be engaged by the mechanism C to be hereinafter more fully described.

The straps or bands 3 are joined to, or connected with the belt 2 by straps 6 which 65 prevent the bands 3 from sliding off the aviator's legs when he is walking around out of the machine.

Straps 7 are secured to either side of the belt 2 and have snaps 8 on their free ends 70 which are adapted to be connected to the mechanism C, in the same manner as the snaps 5.

The mechanism C is preferably positioned directly under the seat of the aviator and 75 has two catches 9 on either side. The catches 9 being operated by means of a handle 11 which is rigidly secured to a transverse shaft 12, the shaft 12 being freely journaled on either end in the brackets 13 and 14 80 which are secured to the frame A of the machine. Rigidly secured to the shaft 12 between the brackets 13 and 14 are elongated links 15 which are pivotally connected to adjacent ends of the rods 16, the other 85 ends of the rods 16 being pivotally connected to the catch bolts 10. The catches 9 are formed with slots or openings 17 which are adapted to be closed by the bolts 10 when the handle 11 is placed in a forward 90 position as is illustrated in Figs. 1 and 2.

The handle 11 has a spring dog 18 of the ordinary construction which is adapted to engage in the notches 19 and 20 formed in the quadrant 21 when moved into the different positions to hold the handle rigidly in place. The quadrant 21 is formed as a part of the bracket 13. A coil spring 22 is positioned on the end of the shaft 12 between the sides of the bracket 13 and is secured 95 on one end to the bracket 13 and on the other end to a pin 23 which passes through the shaft 12, thus when the lever is released from its forward position the spring will tend to throw it back thereby turning the 100 shaft 12 and withdrawing the bolts 10 from the slots 17.

When the operator or aviator takes his position in the seat of the aeroplane he will buckle the snaps 5 and 8 in the catches 9 on the bolts 10, with the lever or handle in the 110 position illustrated in Figs. 1 and 2 and

when he desires to release himself from the machine he simply needs to release the handle 11 thus completely withdrawing the bolts 10 from the catches and simultaneously 5 releasing the snaps 5 and 8.

It is obvious that the straps 4 and 7 can be of elastic material so as to resiliently hold the aviator in his seat and it is also evident that the harness straps can be sewed to the 10 aviator's suit or made a part of the same in any suitable manner. It is also evident that rings can be used in place of the snaps 5 and 8.

While I have illustrated one form of device 15 attached to an aeroplane frame, I desire to have it understood that this is only illustrative and my invention can be carried out by other means and applied to other devices within the scope of the following 20 claims.

Having described my invention, what I claim as new is;

1. In a safety device for aviators, comprising, a belt adapted to be secured about 25 the waist of the aviator, straps extended from said belt, straps adapted to be secured about each leg of said aviator, having depending straps therefrom and means for detachably engaging the free ends of said 30 extending and depending straps to hold said aviator in an aeroplane, said holding means being adapted to simultaneously release said straps and thereby release said aviator.

2. In a safety device for aviators, comprising, means for holding the aviator about 35 the waist and by each leg, means for connecting said holding means to the frame of an aeroplane to securely hold said aviator in said aeroplane and means for simultaneously 40 releasing said connecting means to free said aviator from engagement with said aeroplane.

3. In a safety device of the class described, comprising, a belt for encircling the 45 waist of an aviator, bands adapted to encircle the legs of said aviator, straps connecting said belt and bands to the frame of an aeroplane to securely hold said aviator in said aeroplane and means for simultaneously 50 releasing all of said straps thereby releasing said aviator from said aeroplane substantially as described.

4. In a safety device of the class described, comprising a belt for encircling the 55 waist of an aviator, bands adapted to en-

circle the legs of said aviator, straps connecting said belt to said bands to prevent them sliding off the legs of said aviator, straps connecting said belt and bands to the frame of an aeroplane to securely hold said 60 aviator in said aeroplane and means for simultaneously releasing all of said straps thereby releasing said aviator from said aeroplane substantially as described.

5. In a device of the class described, comprising, a belt adapted to encircling the waist of an aviator, bands adapted to encircle the legs of said aviator, straps connecting said belt and bands to the frame of an aeroplane to securely hold said aviator 70 in said aeroplane, snaps on the end of said straps, said snaps being adapted to engage on the frame of said aeroplane to detachably hold said aviator to said aeroplane and means for simultaneously releasing all of 75 said snaps, thereby releasing said aviator from said aeroplane substantially as described.

6. In a safety device of the class described, comprising means for holding the 80 body of an aviator, means for holding the legs of said aviator, catches secured to the frame of the aeroplane, means connecting said body and legs holding means to said catches and means for simultaneously releasing 85 said catches to release said aviator from said aeroplane substantially as described.

7. In a safety device of the class described, comprising a belt adapted to encircle the body of an aviator, bands for each leg of 90 said aviator, catches secured to the frame of an aeroplane, straps connecting said belt and bands to said catches and a handle connected to said catches, whereby said catches can be opened to release said straps and release 95 said aviator from said aeroplane.

8. In a safety device of the class described, comprising means for holding the body of an aviator, means for holding the legs of said aviator, catches secured to the 100 frame of the aeroplane straps secured to said body and legs holding means having snaps secured to their free ends, catches secured to the frame of said aeroplane, said snaps being adapted to snap into said 105 catches and means for simultaneously releasing all of said snaps from said catches by said aviator, substantially as described.

KNUTE W. OLSON.
